COMBINED SAND BOX AND TABLE

Ralph E. Axe, 550 W. College Ave., York, Pa.

Filed Mar. 17, 1959, Ser. No. 55,039

Term of patent 14 years

(Cl. D34—5)

Fig. 1 is a perspective view of a combined sand box and table showing my new design.

Fig. 2 is a partially exploded end elevation of the combined sand box and table shown in Fig. 1 and illustrating the top of the play table elevated above the sand box.

Fig. 3 is a partially exploded side elevation of the combined sand box and table shown in Fig. 1 and illustrating the top of the play table elevated above the sand box, as in Fig. 2.

I claim:

The ornamental design for a combined sand box and table, as shown and described.
